SHOE CLEAT

Ira Irl Tubbs, Superior, Wis.

Application April 4, 1931, Serial No. 527,637

7 Claims. (Cl. 36—59)

This invention relates to shoe cleats such as used by football players or the like; the principal object of the instant invention being to provide a simple, separable, adjustable cleat, the tip of which 5 may be renewed or adjusted longitudinally from time to time to compensate for wear or other modification of the tip as by damage or the like.

Another object is to provide novel means whereby to insure against the tip being accidentally 10 dislodged.

Another object is to provide such a structure whereby in the event of the tip becoming somewhat loosened in the base portion, support against lateral stress is at all times maintained.

Still other objects and advantages of the novel 15 structure will appear in the further description thereof.

Referring now to the accompanying drawing, forming part of this application, and wherein like 20 reference characters indicate like parts:

Figure 1 is a vertical central section, partly in elevation, of my improved cleat assembled as in use.

Figure 2 is a similar view of the cleat with the 25 tip partly applied thereto.

Figure 3 is a top plan view of the assembled cleat.

In Figure 1, 25 represents the base portion of the cleat which is fastened to the sole of the shoe 30 as by a plurality of nails or screws through circumferentially spaced holes 3 adjacent the outer edge thereof, and which holes are formed directly through the tapered body of the cleat or calk rather than being through a flange formed upon such base portion as sometimes practiced; it being 35 found that a substantially conically shaped calk throughout is the preferred type, wherein the base portion, at least, is of concaved or straight form, the same being less apt to gather mud or dirt than one having sharp angles concentrically 40 thereabouts, and also one having the greatest thrust area possible in proportion to its size and permit of the attaching means being applied externally of the bore in the base portion of the calk. It is obvious for such attachment that the 45 holes for the attaching means are counterbored through the inclined surface of the calk base and then preferably countersunk.

The convenient longitudinal adjustment of the tip of such a shoe cleat or calk may be desirable for several reasons, for example, if worn down within objectionably close proximity to the free 50 end of the base, the tip may be removed entirely and replaced by a new one, or adjusted to a new 55 position within the base, and one or more shim-

ming washers, such as shown at 6, may be placed upon the base 25, and the tip returned to its position thereon and tightly screwed against said washer or washers.

The base of the calk is concaved externally and provided with an axial bore 26 in the lower end thereof, extending approximately half the length of the base. A smaller bore 27 extends downwardly from the upper end into the base, providing a central bore communicating with the bore 26 and through which is positioned the bolt 28. The bore 26 is hexagonal in shape to accommodate and fit the head 29 of the bolt and prevent same from turning, and the upper end of the bolt is externally screw threaded for the reception of the tip 30 which is preferably of the proper consistency of rubber. However this tip is novel in that it is provided with an internally screw threaded sleeve 31, securely incorporated therein, which sleeve extends downwardly materially below the base of the tip so that it is readily extendable within the bore 27 of the base of the cleat. Intermediate of the head of the bolt and bottom of the bore 26 is placed a spring washer illustrated at 32, it being 25 only of a single convolution so as to act as a lock washer when forced together and as a means to bias the bolt towards its withdrawal position and prevent it from extending beyond the upper end of the base 25. The object of such 30 construction is to insure against possible protrusion of the bolt beyond the upper end of the base 25 in the event of the tip 30 with its sleeve 31 becoming dislodged therefrom, to avoid any possibility or danger of injury to a player 35 by the bolt, and at the same time providing means for convenient application of another tip inasmuch as the protruding end of the sleeve 31 is readily extendable into the bore 27 for screw 40 threaded engagement with the bolt, and when the tip is screwed home the bolt will be drawn tightly against the combination spring and lock washer 32. This tip may be provided with circumferential notches like those shown in Figure 45 3, or may have spaced holes therein for the reception of a wrench for turning it on or off as desired.

From the foregoing it is evident that I have devised a practical way in which to combine with a fixed base on the sole of a shoe an adjustable tip, and it is evident that further modifications of the device may be resorted to without departing from the spirit of the invention broadly.

Having thus described my invention, what I claim and desire to secure by Letters Patent, is:

1. A shoe cork comprising a base attachable to the wearing surface of a shoe sole, a tip, and means carried by the base for screw threadedly receiving the tip, said means comprising a bolt reciprocable within the base, but non-rotatable therein. 5
2. A shoe cork comprising a base adapted for fixed attachment to the wearing surface of a shoe sole, a tip, and screw threaded means one 10 end of which is reciprocably but non-rotatably held in the base and the other end of which is screw threadedly engaged by the tip.
3. A shoe cork comprising a non-resilient base for fixed attachment to the wearing surface of a 15 shoe and having an opening therein, screw threaded means reciprocably but non-rotatably held within said opening, and a removable tip having screw threaded means adapted for attachment to said screw threaded means in the 20 base.
4. A shoe cork comprising a base for fixed attachment to the wearing surface of a shoe, a tip, and screw threaded means one end of which is non-rotatably held in the base and the other 25 end of which is screw threadedly engaged by the tip, and means adapted to bias said screw threaded means from projecting beyond the outer edge of the base when not engaged with a tip.
5. A shoe cork comprising a rigid base adapted for non-resilient attachment to the wearing surface of a shoe sole, a tip, and screw threaded means one end of which is reciprocably but non-rotatably held in the base and the other end 5 screw-threadedly engaged by the tip.
6. A shoe cork comprising a rigid base adapted for fixed attachment to a shoe sole, said base having an opening therein and a screw threaded member non-rotatably mounted upon said base but transversely movable thereof, in combination with a tip adapted to cooperate with said base, screw threaded means upon said tip adapted to cooperate with the screw threaded means upon the base to rigidly and removably secure the tip 10 to the base.
7. A shoe cork comprising a rigid base adapted for fixed attachment to a shoe sole, said base having a socket formed in one face, an opening through the top of said socket and a screw 15 threaded member positioned in said socket and held against rotation by engagement with the walls of the socket but transversely movable thereof, in combination with a tip adapted to cooperate with said base, screw threaded means 20 upon said tip adapted to cooperate with the screw threaded means upon the base to rigidly and removably secure the tip to the base.

IRA IRL TUBBS.
